US0D1083543S

(12) **United States Design Patent** (10) **Patent No.:** **US D1,083,543 S**
(45) **Date of Patent:** **** Jul. 15, 2025**

(54) **PERFORATED BOARD**

- (71) Applicant: **DELI GROUP CO. LTD**, Ningbo (CN)
- (72) Inventors: **Chong Zheng**, Zhejiang (CN); **Hongyu Qi**, Zhejiang (CN); **Yuangang Yang**, Zhejiang (CN)
- (**) Term: **15 Years**
- (21) Appl. No.: **35/521,443**
- (22) Filed: **May 6, 2024**

(80) **Hague Agreement Data**

- Int. Filing Date: **May 6, 2024**
Int. Reg. No.: **DM/237862**
Int. Reg. Date: **May 6, 2024**
Int. Reg. Pub. Date: **Jun. 28, 2024**
- (51) **LOC (15) Cl.** **08-05**
(52) **U.S. Cl.**
USPC **D8/71; D6/553**
- (58) **Field of Classification Search**
USPC D8/71; D6/422, 428, 491, 509, 511, 469, D6/553
CPC B25H 3/04
See application file for complete search history.

Primary Examiner — Barbara Fox
Assistant Examiner — Harold E Blackwell, II

(57) **CLAIM**

The ornamental design for a perforated board as shown and described.

DESCRIPTION

The patent or application file contains at least one drawing executed in color. Copies of this patent or patent application publication with color drawing(s) will be provided by the Office upon request and payment of the necessary fee.

1. Perforated board
  2. Perforated board
  - 1.1 : Front
  - 1.2 : Back
  - 1.3 : Left
  - 1.4 : Right
  - 1.5 : Top
  - 1.6 : Bottom
  - 1.7 : Perspective
  - 1.8 : Perspective
  - 2.1 : Front
  - 2.2 : Back
  - 2.3 : Left
  - 2.4 : Right
  - 2.5 : Top
  - 2.6 : Bottom
  - 2.7 : Perspective
  - 2.8 : Perspective
- Design 1 is the main design, design 2 is the relevant design; the color in design 1 and design 2 form no part of the claimed designs.

1 Claim, 16 Drawing Sheets
(16 of 16 Drawing Sheet(s) Filed in Color)
